UNITED STATES PATENT OFFICE.

MAGNUS LARSEN, OF NEW YORK, N. Y., ASSIGNOR OF ONE-HALF TO FREDERICK F. HESPE, OF JERSEY CITY, NEW JERSEY.

ELECTRIC-LAMP SOCKET.

1,109,589.

Specification of Letters Patent.

Patented Sept. 1, 1914.

Application filed January 18, 1908. Serial No. 411,456.

To all whom it may concern:

Be it known that I, MAGNUS LARSEN, a subject of the King of Norway, residing in the borough of Manhattan, city of New York, in the county of New York and State of New York, have invented a new and useful Electric-Lamp Socket, of which the following is a specification.

This invention relates to electric lamp sockets, such as used for chandeliers and electric light fixtures.

It has for its object to provide an adjustable socket for electric lamps, which shall be so constructed as to allow of a raising or lowering of a lamp attached, and of setting same at many and varying angles to a base supporting the adjustable socket and firmly held in such position. Heretofore, when electric lamp sockets of the character described were thus to be adjusted, recourse had to be had to extra constructed devices, such as swing joints or fittings, which either were at best difficult to wire or else would wear and chafe and expose the wires and also add to the expense of the fixture.

The elimination of such joints with their undesirable features is the aim of the present invention. To accomplish this I construct a socket cover in a new and novel way, which briefly described is as follows: A tubular sleeve adapted to receive and retain in place an insulated electric lamp base receptacle with contacts, said tubular sleeve, which may be about the length of the usual electric lamp socket without its cap, has at the end opposite the lamp base entrance two lateral members having circular or annular hollow spaces facing each other internally, a short distance apart, in a parallel plane perpendicular to the tubular sleeve and space. Said members rotatively mounting and inclosing in said annular or circular space an annular or circular central member carrying means for attaching same member to a desired base or fixture, and all the parts are so arranged, that the lateral members with the lamp attached may be bodily rotated or turned upon said central member, and the lamp be thus presented and firmly supported at many and varying angles to its base. All without injury to the electric circuit contacts.

As a better understanding of the adjustable socket will be had from a detailed de-

scription of a practical embodiment thereof, such description will now be given, reference being had to the accompanying drawings in which:

Figure 1 is an elevation of the adjustable socket. Fig. 2 is an elevational view of Fig. 3 at right angle with same. Fig. 3 is an elevational side view of Fig. 1 through the center with central member left out. Figs. 4 and 5 are vertical sectional views of the central member taken one at right angles to the other. Fig. 6 is a vertical sectional view of Fig. 2 through the center at right angle with same. Fig. 7 is same as Fig. 1 but with a somewhat different construction. Fig. 8 shows members A and B in a vertical central sectional view and an inclosed porcelain base in elevation. Fig. 9 shows a preferred type of a porcelain base.

Similar letters refer to similar parts throughout the several views.

The adjustable socket cover as shown in Fig. 1 consists of three separate parts or members, two lateral members or parts "A" and one central member or part "B." The two lateral members "A" are identical with each other, as if made from a single die or mold, so the description of one of the members A will be the same as that of the other. The one end of the lateral member A, which is to receive or cover the lamp base receptacle, is so formed, that when the said two lateral members A are united, they present a cylindrical or tubular sleeve in shape and size preferably similar to such parts of the commonly used electrical lamp sockets, that incloses or covers the porcelain-base with its lamp receptacle. This end of the members A is therefore semi-tubular or semi-cylindrical. At the end opposite the lamp entrance the member A merges into a hollow form, which may be hemispherical or other shape. The internal face of this part of member A is annular or circular, and its edges formed into an annular or circular guideway, intended to receive an annular or circular member B. This guideway, is shown in the sectional view Fig. 6 as a short extending flange situated a short distance from the internal edges of the semi-tubular sleeve and overlapping the member B as is shown in Fig. 1. I do not, however, limit myself to the particular form of the guideway as I am aware that various changes

may be made in the construction. The hollow space of member A should be of a depth about on line with the extremity of the diameter of the widest part of the cylindrical or tubular sleeve, or rather of a depth great enough to allow passage for an electric conductor on either side of the central member B; and clear of same. Said member A is provided with an opening on an axial line through the center of its annular or circular space for the passage of an insulated axial rod F with outer threaded ends. Said member A being also provided throughout with insulating material Y adapted in shape and extent to the entire member and firmly held in place by means of a small metal bushing P as shown in Fig. 6, or may be also otherwise held. Said insulating material not extending further, however, in the annular or circular part of member A, than to the circular or annular guideway as shown in Fig. 6. The central part B consists of an annular or circular member adapted to the circular or annular guideways of the members A, when in position, in such a way that the members A may be bodily rotated upon said member B.

A nozzle C similar to and for the same intent and purpose as the nozzles of the ordinary caps for the electric lamp sockets is rigidly attached to said member B. This nozzle may be cast as part of the member B, or also fastened in the manner shown in Fig. 8 or with a screw nut D as shown in Figs. 4 and 5, which may be soldered to the member B or otherwise held. It should be noticed that the screw threaded part of the nozzle does not extend through the ring, a plain space is left as it passes through same and is intended to allow a bodily rotation of the entire socket upon said nozzle means being had to limit the turning movement to the circle. An opening is had throughout the nozzle C and member B for the passage of electric wiring M to the inclosed lamp base contacts. This member B, preferably a ring as shown in the drawings, in order to be fully insulated may be provided with a fiber ring L internally, or other insulating material with opening for and passage of the electric wiring.

In Fig. 8 is shown the adjustment of the several parts. The member A and the member B are shown in a vertical central sectional view and the inclosed porcelain-base with its lamp-receptacle attached in elevation. An axial rod F passing through the members A and B serves to bind the said members together and also to retain the electric lamp in any of its desired positions by means of the thumbnuts E. Washers J being interposed between these said thumb-nuts and members A to facilitate the operation of the adjustment. Said axial rod F is, however, not essential, as it merely is

intended where special security is needed and may ordinarily be dispensed with. The said rod F may be insulated as shown by piece K. A porcelain base traversed by a rectangular channel O, through the center of its upper extremity and having grooves Q and Q', one on each side of same for the passage of electric wires, is shown in Figs. 8 and 9. This groove O serves as an insulation for the annular edges of the member B, when same leave the annular edges or guideways of the members A and also serves to retain in place the fiber ring L of member B. The sides of said channel O being parallel to each other and parallel to the motion of the tubular sleeve, offer therefore, no obstruction to the free rotation of the lateral members A on the tubular ring B. The channel O serves also the purpose of preventing a turning movement on part of the porcelain base during the insertion of an electric lamp into the screw threaded metallic sleeve rigidly attached to said porcelain base. The rubber covered wires passing in through the nozzle C are led as in the usual or ordinary socket to their contact places and secured by the usual means.

In Fig. 7 is shown a slightly modified form of the adjustable socket consisting of two parts adapted to be secured to each other. One part being a cylindrical sleeve inclosing a porcelain base with a lamp receptacle attached and the other part a cap or cover for same, consisting of a ring adapted to slip over and be secured to said cylindrical sleeve and having two lateral interiorly hemispherically hollowed members soldered or otherwise rigidly attached thereto, said lateral members having their interior edges formed into an annular or circular guideway for the reception of a tubular ring provided with a short screw threaded tubular nozzle allowing a free rotation of the inclosing members upon said inclosed tubular ring. Said cap and said cylindrical sleeve serving in every respect same purpose and idea as the socket described in the other figures.

What I claim is:

1. As an article of manufacture an electric lamp socket casing consisting of three members relatively adjustable and held together by a clamping device, and having an opening for entrance of electric wires to the inferior of said three members, which opening is situated in the center member, two of the said members, when joined, being tubular in form at one end and adapted to receive a porcelain base with a lamp receptacle and the other end of said two members being in the nature of a hollow bifurcated sphere adapted to give play room for electric wires attached to said porcelain base, the third member being a ring adapted to occupy the space produced by the bifurcation of said

spherical portion of the said two members, said ring having a threaded hollow nozzle attached for the entrance of aforesaid electric conductors to the aforesaid porcelain base and for fastening said ring to a fixture by means of its threaded nozzle.

2. As an article of manufacture an electric lamp socket casing consisting of three members, relatively adjustable, and held together by a clamping device and having an opening for entrance of electric wires to the interior of said three members, which opening is situated in the center member, two of the said members, when joined, being tubular in form at one end and adapted to receive a porcelain base with a lamp receptacle, and the other end of said two members being in the nature of a hollow sphere, bifurcated to receive and hold in place the third member, a ring, by the aid of a clamping device in the shape of an axial rod passing axially through said three members, and in the spherical portion of same, said axial rod also serving to hold the three members in any position of relative adjustment.

3. As an article of manufacture an electric lamp socket casing consisting of three members relatively adjustable and held firmly together by a clamping device and having an opening for the entrance of electric wires which do not pass out of said three members, but terminate within them, two of the said three members when joined being tubular in form at one end and adapted to receive a porcelain base with a lamp receptacle, and the other end of said two members being in the nature of a bifurcated sphere, hollow, to give playroom for electric wires entering through the third member, a ring, which ring is adapted to occupy a space produced by the bifurcation of said spherical portion of said two members, said electric wires passing through a nozzle attached to said ring and to the wire terminals of said porcelain base.

4. As an article of manufacture an electric lamp socket, comprising a porcelain base with a lamp receptacle and electric conductors leading to said porcelain base, a casing to inclose said porcelain base with its lamp receptacle and said conductors, said casing consisting of three members relatively adjustable and held together by a clamping device, two of said members when joined being tubular in form at one end and adapted to hold said porcelain base with lamp receptacle, and at the other end being in the nature of a sphere, hollow, so as to give playroom for electric wires, and bifurcated with space for reception of the third

member, a ring, upon which said two members are adapted to revolve, while means are being had in the way of an axial rod passing axially through said three members 65 in the spherical portion of same and thumb nuts on ends of said axial rod to firmly clamp said two members at any angle of said ring.

5. The combination in a lamp socket of a porcelain base with a lamp receptacle and wire terminals and electric conductors leading to said wire terminals with a casing to inclose said porcelain base with its lamp receptacle and electric conductors, said casing 75 consisting of three members relatively adjustable by the aid of an axial rod passing through said three members, and thumb nuts upon the threaded ends of said axial rod, two of the said three members being 80 tubular in form at one end for the reception of aforesaid porcelain base with its lamp receptacle and electric conductors and the other end of said two members being in the nature of a hollow bifurcated sphere adapted 85 to inclose and revolve on the third member, a ring, said ring having a hollow threaded nozzle attached or integral therewith for the fastening of said ring to a fixture and to allow said electric conductors 90 aforesaid to enter the interior of said three members, one conductor on each side of the interior of said ring to terminate at the terminals of said porcelain base.

6. The combination in a lamp socket of a porcelain-base with a lamp receptacle and wire terminals and electric conductors leading to said wire terminals with a casing to inclose said porcelain-base with its lamp receptacle and electric conductors, said casing 100 consisting of two telescoping members, one of said members being tubular in form and adapted to inclose said porcelain-base with its lamp-receptacle and wire terminals, and the other of said members being in the nature of a hollow, annular or globular body, 105 the one end of which terminates in an annular band or ring, adapted to telescope with said tubular member and fasten thereto, and said annular or globular body being bifurcated to provide space for a rotatable ring with a hollow nozzle, said annular or globular body having space on either side of said ring, interiorly for the passage of electric conductors entering aforesaid nozzle 115 and terminating at the wire terminals of aforesaid porcelain-base.
